UNITED STATES PATENT OFFICE.

THOMAS E. DEMPSEY, OF NEW YORK, N. Y.

VULCANIZING DEVICE

1,205,599.

Specification of Letters Patent. Patented Nov. 21, 1916.

Application filed August 27, 1914. Serial No. 858,800.

To all whom it may concern:

Be it known that I, THOMAS E. DEMPSEY, a citizen of the United States, residing at New York, in the county of New York and State of New York, have invented new and useful Improvements in Vulcanizing Devices, of which the following is a specification.

This invention relates to improvements in portable vulcanizers of that class comprising a cup or receptacle for retaining a fluent fuel, which when ignited, serves to heat the receptacle in a manner to vulcanize the material therebeneath. This class of devices have heretofore been provided with conducting bodies for conducting the heat from the flame through the fluent fuel into the bottom of the receptacle, the face of the latter transmitting the heat to the patch. Difficulties have been encountered in prior devices of this character because of the face that the heat has been distributed in a manner to raise practically all portions of the vulcanizer to the same temperature. Now to properly patch a tire or shoe, it is necessary to employ a patch which is thicker at its central portion than at its margin, and further, the repair rubber with which the puncture or hole is filled, is immediately below the thicker portion of the patch and therefore efficient vulcanization requires a higher temperature over the central portion of the patch than radially outwardly thereof. Furthermore, damage frequently results if the shoe or tube is unduly heated at points beyond the patch, or outside thereof, and as the vulcanizer extends considerably beyond the patch when the latter is of the usual dimension, it will be seen that uniform heating of the vulcanizer to the required temperature dangerously subjects the shoe or tube to unnecessary heat.

Now it is the primary object of this invention to provide a vulcanizer wherein the highest temperature is obtained where the patch is thickest and wherein the temperature is gradually reduced over portions of the patch not requiring the highest temperature, this feature of the invention serving to safely distribute the heat in accordance with requirements.

A further very important feature of the invention consists in providing the vulcanizer with a heat-conducting body and a surrounding wall, said body extending above or beyond the edge or margin of the wall

near the central portion of the vulcanizer, and receding toward said margin radially outwardly from the central portion, this construction serving to cause the combustion supporting air to seek entrance beneath the affluently generated gas over the margin of the surrounding wall thereby causing the flame to column or cone about the central portion of said conducting body, thereby further enhancing the novel heat distributing feature by localizing flame action away from outermost portions of the vulcanizer.

My invention has other novel features which will be more fully described in connection with the accompanying drawing, and which will be more particularly pointed out in and by the appended claims.

In the drawing:—Figure 1 is a plan view of the most improved embodiment of my invention. Fig. 2 is a sectional view on line 2—2 of Fig. 1, showing the manner in which a patch is applied to a tube. Fig. 3 is a bottom plan view of the base of my improved vulcanizer.

Like characters of reference designate similar parts throughout the different figures of the drawing.

As illustrated, 1 designates a vulcanizer base which has a substantially circular central portion and projecting base arms 2, extending therefrom. The bottom of said base is suitably hollowed out, as indicated at 3 and 4, to reduce its weight and retain sufficient rigidity, the upper face of said base being substantially flat. Threaded studs 5 project upwardly from said base for a purpose hereafter described. In the utility of my invention, the base is only necessary in repairing a tube, means such as chains being used to secure the vulcanizer upon a shoe, when repairing the latter, in the usual manner.

My vulcanizer proper, comprises a receptacle 6 having a surrounding wall 7 terminating in an upper margin or edge 8. Extending outwardly from the receptacle 6, at diametrically opposite points, are arms 9 which are hubbed at 10 and which are provided with bores to receive the studs 5. Means such as winged nuts 11 may be employed to force the receptacle 6 against an interposed tube 12. The arms 9 project from the receptacle at points slightly above the bottom 13, of the latter, and I preferably concave the bottom 13 and highly polish the lower or vulcanizing face thereof. Further

more, the outer annular edge 14 is rounded off so as not to in any way injure the tire as a result of heated pressure engagement therewith.

5 The receptacle 6 serves to receive and contain a suitable character of fuel, which will preferably be a fluent fuel such as gasoline, kerosene, or the like. Rising from the bottom 13 is a heat-distributing or conducting body which is preferably formed integral with the receptacle 6, and which is indicated as a whole at 15. A preponderant mass of said body is located centrally in the receptacle 6, and is shown in the form of an upright post 16. In some cases I may advantageously annularly fillet the bottom portion of the post 16, as indicated at 17, so that it will merge into the upper face of the bottom 13 and increase the cross section of the post 16 at its juncture with the bottom 13. Said conducting body also comprises flanges 18 which radiate from the post 16 and which extend from the bottom 13 to a level with the top of post 16, these flanges being reduced in thickness with respect to cross section of post 16. At their outer ends, these flanges 18 are bifurcated and extend tangentially to the wall 7, as indicated at 19, and the flanges 19 are reduced in thickness with respect to flanges 18 and do not extend into contact with wall 7. Thus the entire area of the receptacle 6 is open for free passage of the fluent fuel so that the latter can pass about and seek its level when poured in at any one point. It will be seen by reference to Fig. 2, that the central portion 16, and the flanges 18, extend above the margin 8, but the flanges 19 recede from 20 to 21 on curved lines so that the outer edges of the flanges 19 will be practically on a level with edge 8. Now it will be clear that I not only dispose a very great preponderance of the mass of said conducting body, centrally of the receptacle, but I also gradually reduce the mass both in height and thickness radially outwardly from the central portion.

In repairing a tube, the latter will be placed upon the base 1 and the receptacle will be clamped in position over a suitable patch 22, which is shown thicker at its central portion than at its marginal edges. The hole or puncture will be filled with repair rubber 23 and it will be necessary in vulcanizing the patch to cause this extra thickness at the center of the latter to merge with the tube. Now it will be seen that the greatest mass is disposed over the thickest portion of the patch and as the flames from the ignited fuel ascend, the conducting body will conduct a greater amount of heat over the center of the patch than at its outer margin, and because of the gradual radial reduction of the flanges 18 and 19, there will be a gradual diminution of heat transmission

toward the outer margin of the patch. Because of the fact that the column 16, rises above the edge 8, the flame will cone about the post 16 and rise in a central body away from the outer or surrounding wall 7, by 70 reason of the fact that air necessary to support combustion, will seek ingress to the receptacle 6, over the edge 8, and under the affluently generated gas. Thus the flame will not only be localized centrally of the 75 receptacle, but its heating efficiency near the outer wall 7, will be so attenuated and diminished that portions of the tube lying beyond the margin of the patch and being in engagement with the vulcanizing face of the 80 bottom 13, cannot possibly be heated to an injurious extent.

I have found that the best results are obtained by forming the vulcanizer of aluminum and copper, a practical, economical and 85 efficient though not a necessary proportion being eighty-five per cent, aluminum and fifteen per cent, copper, the copper being used to strengthen the aluminum against bending or breaking under any usual stress 90 that might be imposed. With a vulcanizer composed of these materials, I can provide the bottom 13 with a very highly polished vulcanizing face which prevents the latter from adhering either to the patch or to other 95 portions of the rubber being repaired. I regard this as a highly important feature of my invention which has been found in practice to effectively meet requirements.

With a vulcanizer made of this composition, I find I can vulcanize with a lesser amount of fuel than has heretofore been necessary.

It is believed that the advantages and utility of my invention will be fully understood from the foregoing description, and while I have herein shown and described one form of my invention, I do not wish to be limited thereto except for such limitations as the claims may import.

I claim:

1. In a vulcanizing device, an open receptacle for fluent fuel having a bottom forming a vulcanizing face, said bottom having a heat conducting body projecting therefrom into said receptacle for conducting heat from the flame to said bottom, a preponderance of the mass of said heat conducting body being centrally disposed with respect to said receptacle to impart a higher temperature to the central portion of said bottom than to radially outer portions thereof, substantially as described.

2. In a vulcanizing device, an open receptacle for fluent fuel having a bottom forming a vulcanizing face and provided with a surrounding wall, and a heat conducting body rising from the bottom of said receptacle and having a central portion extending above the margin of said surround

ing wall and radially outer portions receding toward the margin of said wall, a preponderance of the mass of said conducting body being centrally disposed with respect 3 to said receptacle to impart a higher temperature to the central portion of said bottom than to radially outer portions thereof, substantially as described.

3. In a vulcanizing device, an open receptacle for fluent fuel having a bottom forming a vulcanizing face and provided with a surrounding wall, and a heat conducting body rising from said bottom and having a central portion extending above the margin of said wall and radially outer portions receding toward said margin, a preponderance 15 of the mass of said body being disposed at the center of said body with a gradual reduction of the mass in radially outer portions of said body, substantially as described.

4. In a vulcanizing device, an open receptacle for fluent fuel having a bottom forming a vulcanizing face and provided with a surrounding wall, a post rising from the bot- 20 25

tom of said receptacle and having flanges extending radially toward said wall with their terminal ends forked or bifurcated and extending toward but not to said surrounding wall, said post and flanges being integral 30 with said bottom to conduct heat from the flame thereto, substantially as described.

5. In a vulcanizing device, an open receptacle for fluent fuel having a bottom forming a vulcanizing face, and provided with a surrounding wall, and a heat conducting body rising from said bottom and extending above the margin of said wall, a preponderance 35 of the mass of said body being disposed centrally thereof to impart a higher temperature in the central portion of said bottom than to radially outermost portions thereof, substantially as described.

In testimony that I claim the foregoing as my own, I hereby affix my signature in the presence of two subscribing witnesses.

THOMAS E. DEMPSEY.
